DEVICE FOR MAKING BOX BLANKS

Robert F. Moritz, Laurel Springs, N. J., assignor to
 Samuel M. Langston Co., a corporation of New
 Jersey

Application April 8, 1939, Serial No. 266,782

12 Claims. (Cl. 164—28)

The present invention relates to machines for making box blanks, of the type in which a rectangular board or sheet has score lines to provide side panels, and slots and score lines to form end closure flaps. The invention relates particularly to the means for forming a flap or extension along one edge of one side panel, and adapted to be folded over the edge portion of another panel and be secured thereto to form the tubular body portion of the box.

As the securing is ordinarily effected by wire staples, and is commonly referred to as stitching, the flap will be referred to hereinafter as the stitch flap, although this does not imply any particular method of securing it to the panel at the opposite side of the blank.

One object of the present invention is to provide a new and improved attachment, adapted to be adjustably secured to a rotary slitter head, for cutting the ends of the stitch flap to make it of the proper length in respect to the length of the panels.

Another object is to provide a slitter attachment of the general type above referred to, having new and improved means for quickly and simply adjusting the effective depth of the cutting blade and for clamping it in adjusted position.

Various other objects and features of the invention will be apparent from the following particular description, and from an inspection of the accompanying drawing, in which:

Fig. 1 is a fragmentary perspective of a mechanism for slotting and slitting an advancing sheet to form a box blank, and shows the slitter head with stitch flap cutting attachments embodying the present invention.

Fig. 2 is a vertical section on an enlarged scale through one of the stitch flap attachments at right angles to the axis of the slitter head,

Fig. 3 is a radial section taken on line 3—3 of Fig. 2,

Fig. 4 is a perspective of the main section of the knife holder,

Fig. 5 is a perspective of the clamping section of the knife holder,

Fig. 6 is a perspective of the cam member for adjusting the cutting blade radially and holding it against inward movement, and

Fig. 7 is a plan view of a box blank with a stitch flap formed by the mechanism of the present invention.

The machine illustrated is adapted to form a corrugated box blank shown in Fig. 7 with a series of longitudinally extending score lines 10, along which the body of the blank may be folded

to form the four sides of the box, slots 11 extending longitudinally from the ends of said score lines 10 and co-acting with transverse score lines 12 to define the end closure flaps of the box. The blank has the stitch flap 13 on one side of the blank adapted to be stitched to a panel 14 on the opposite side of said blank, to hold said blank in tubular folded position.

A box blank machine of the general type to which the present improvements may be applied is shown in Patents Nos. 1,850,800 and 2,117,220.

The slotting mechanism includes a series of axially spaced upper slotting heads 15, only one being shown, cooperating respectively with lower slotting heads 16, and splined to an upper shaft 17. Each of these upper slotting heads 15 carries circumferentially spaced slotting blades 18, for forming the slots 11 as the blank A is advanced as shown in Fig. 1.

At one end of the series of slotting heads 15, there is provided a rotary slitting or trimming mechanism, which may be used for trimming the entire side of the blank A along a straight line, to form the type of box blank in which the straight sides are held in butting relationship by an adhesive strip, or which may be easily and readily converted to form the stitch flap 13 on one side of the blank. For that purpose, there is provided an upper slitter head 20, splined to the upper shaft 17 for axial adjustment therewith, and cooperating with a lower slitter head 19. This slitter head 20 has a hub 21 of large diameter, and a circumferential flange 22 extending radially outwardly therefrom. For forming the stitch flap, a pair of circumferentially spaced arcuate slitting blades 23 are seated on an annular shoulder 24 on the outer side of the flange 22, and detachably secured to the latter by suitable bolts 25 passing through slots 26 in said flange. These blades 23 are adapted to make the side cuts 27, which extend from opposite ends of the flap 13 lengthwise of the blank. The blades 23 are adjustable on the head 20, so that their circumferential spacing conforms with the desired length of the flap 13. The accuracy of the adjustment is facilitated by a graduated tape 28 in a peripheral groove of the flange 22. When no stitch flap is desired, the blades 23 may be replaced by a pair, each extending half-way around the hub, so as to trim the blank to present a straight edge.

When the stitch flap is to be formed, there are provided two attachments 30 and 30a for making the transverse end cuts 31 at the ends of the flap 13. They may be similar, but pref-

erably they are reversely constructed as shown in Fig. 1, to permit them to be adjusted closer together as will be made more apparent hereinafter.

The attachment 30 shown in detail in Figs. 2 and 3 comprises a holder 34, for holding a score knife 35 transversely of and in close proximity to a corresponding arcuate knife 23, said holder having a base 36 presenting a curved surface 31, for seating engagement with the periphery of the hub 21 at one side of the shoulder 24. Means are provided for securing the holder in circumferentially adjusted position. In the specific form shown, said means comprises a circular base flange 38, extending circumferentially from one side of said holder, and receiving a radial clamping bolt 40, having a curved head 41, slidably retained in a T-shaped circumferential groove 42 in the hub 21. For guiding the holder 34 during circumferential adjusting movement, and for holding said holder against movement axially of the slitter head 20, said holder is desirably provided with a ridge or rib 44, extending inwardly from the base of said holder into the narrow or neck portion of the groove 42.

The holder 34 carries cam means for radially adjusting the knife 35, and means for clamping the knife and the cam means in adjusted position. For that purpose, the holder 34 is in the form of a bearing block, having a main body section 46 and a clamping section 47, separable therefrom and defining with said body portion a cylindrical socket 48. As shown, this main holder section 46 presents slightly more than one half of the circumference of the cylindrical socket 48, while the clamping member 47 presents the remainder of said circumference. The two holder sections 46 and 47 present opposed substantially radial faces 50 and 51 respectively at 40 their radially outer ends, between which the knife 35 is held, and opposed faces 52 and 53 respectively at their other ends substantially at right angles to said radial faces. The two separate holder sections 46 and 47 are desirably made 45 first as one integral piece, and then split by a fine saw-cut at the face sections 50—51 and 52—53.

The means for radially adjusting the knife 35 comprises a rotary cam member 56, journaled 50 in the socket 48, and having a circular or cylindrical periphery 57 desirably of about 270° conforming with the curvature of said socket, and a cam periphery 58 of substantially spiral form 55 along the remainder of the circumference of said member, with the high side of said periphery merging into said circular periphery. This cam periphery 58 supports the radially inner edge of the knife 35.

For turning the cam member 56 in its bearing socket 48, said member is provided at one end with a head 60, which projects outwardly beyond the sides of the holder 34, and which is desirably of polygonal shape to receive a suitable turning tool such as a wrench. As the cam member 56 is rotated clockwise as viewed in Fig. 2, the cam surface 58 thereof pushes the blade radially outwardly, until a knife section of desired depth in accordance with the thickness of the corrugated blank extends beyond the knife holder, so that the edge will be exactly or practically in contact with the hard surface of the lower head 19 at the time of cutting.

For moving the clamping member 47 against the cam member 56, to hold said cam member 75 against rotation in adjusted position, and to

retain said cam member in the socket 48 against axial displacement, the cam member 56 is provided with a sector-shaped bolt receiving slot 61 of about 270°, extending transversely therethrough, leaving unslotted a sector-shaped piece 62 of about 90° in the central quadrant of the cylindrical surfaced section of the cam member and diametrically opposite the cam surfaced section. Threaded into a hole 63 of the holder section 46 is a clamping bolt 64, passing loosely 10 through the groove 61, and through a hole 65 in the clamping holder section 47. This clamping bolt 64 terminates at one end in a head 66 of polygonal shape to receive a suitable turning tool, and bears against the outer surface of the 15 clamping member 47.

The sector piece 62 is so disposed, that the cam member 56 can be rotated about 90° to cover the total adjusting range of the cam surface 58, and while the bolt 64 is in position but loosened. 20 When the cam member 56 has been rotated to selective adjusted position, the clamping bolt 64 is turned to move the member 47 into clamping engagement with the circular periphery 57 of 25 said cam member.

By using reverse flap attachments 30 and 30a with the base flanges 38 extending in opposite directions, said attachments can be adjusted to close proximity with their unflanged or shorter sides touching, thereby affording a wide range of 30 adjustment in the length of the flaps.

The holders 30 and 30a are so arranged on the slitter head 20, that the knives 35 extend from or near the circumferential opposed ends of the arcuate blades 23. During the operation of the 35 machine, the blade 23 shown in Fig. 1 in the lower section of the slitter head 20 will make the cut 27 on the forward end of the advancing blank A, and at the end of this cut, the knife 35 on the holder 30a will make the cut 31 defining 40 the forward end of the flap 13. Since the speed of the advancing blank A is correlated with the speed of rotation of the slotting and slitting heads, the knife 35 on the holder 30 will come down on the advanced blank to make the transverse cut 31 defining the rear end of the flap 13. The arcuate knife 23 shown in the upper part 45 of the slitter head 20 will then make the cut 27 on the rear end of the advancing blank, so that the operation of forming the flap 13 will be 50 complete.

The blades 35 may be easily removed for sharpening by merely loosening but not removing the bolt 64. The adjustment by rotation of the cam member may be to take care of wear on the 55 blade, the use of blades of different width, to take care of upper and lower heads, and the use of lower heads of different diameter. The same bolt 64 which clamps the blade also clamps the cam member. Adjustment of the circumferential spacing of the blades does not disturb the radial adjustment. Preferably the heads of the bolts 64, the nuts of the bolts 40 and the heads 60 on the cam members are all of the same size and shape, so that the same socket 65 wrench may be used on all.

When it is desired to make a straight cut across the entire side of the blank, the attachments 30 and 30a are removed, and the two arcuate knives 23 replaced by a single circular knife.

As many changes could be made in the above construction, and many apparently widely different embodiments of this invention could be made without departing from the scope thereof, it is intended that all matter contained in the above 75

description or shown in the accompanying drawing shall be interpreted as illustrative and not in a limiting sense.

Having thus described my invention, what I claim as new and desire to secure by Letters Patent is:

1. A device adapted to be secured to a slitter head, for making the end cuts of a flap extension on one side of an advancing box blank, comprising a knife, a holder for said knife, a member carried by said holder, rotatable about an axis parallel to the axis of said head, and having a surface for supporting said knife in various adjusted positions, and means for simultaneously clamping said knife in adjusted position and clamping said member against rotation.

2. A device for making transverse cuts in an advancing box blank, comprising a knife holder having a socket, a cam member rotatable in said socket, a knife in said holder bearing on the cam surface of said member, whereby rotary position of said cam member determines the radial position of said knife, and means for clamping said knife in adjusted position.

3. A device for making transverse cuts in an advancing box blank, comprising a knife holder having a socket, a cam member rotatable in said socket, a knife in said holder bearing on the cam surface of said member, and means for simultaneously clamping said knife in adjusted position and said cam member against rotation.

4. A device for making transverse cuts in an advancing box blank, comprising a knife holder having a pair of relatively slidable sections conjointly defining a socket, a cam member rotatable in said socket, a knife in said holder between said sections and bearing upon said cam member, and means for clamping one of said sections against said knife to hold said knife in adjusted position.

5. A device adapted to be mounted on a rotary slitter head, for making the end cuts of a flap extension on one side of an advancing box blank, comprising a knife holder having a pair of relatively slidable sections defining therebetween a cylindrical socket, a cam member rotatable in said socket, and having a cylindrical surface along a portion of its periphery conforming with the periphery of said socket, and a cam surface along another portion of its periphery, a knife between said holder sections, bearing against said cam surface, and means for moving said sections relatively towards each other and against said cam member for clamping said knife and said cam member in adjusted position.

6. A rotary device for making transverse cuts in an advancing blank, including a knife holder having a main body section and a knife clamping section movable towards and away from said main body section, and conjointly defining a socket, a bolt extending transversely through said socket for holding said section against relative movement, a cam member rotatable in said socket, and having a slot for receiving the portion of said bolt extending through said socket, to permit limited rotation of said cam member

in said socket, and a knife between said sections and bearing on the cam surface of said cam member.

7. A device adapted to be mounted on a rotary slitter head, for making the end cuts of a flap extension on one side of an advancing box blank, comprising a knife holder presenting a socket, and split along two planes substantially at right angles to each other to form two separable sections, each defining part of the peripheral wall of said socket, a knife in one of the splits between said sections, a rotatable member in said socket for adjusting said knife outwardly from said sections, and means for clamping said sections together and against both said rotatable member and said knife.

8. A device adapted to be mounted on a rotary slitter head, for making the end cuts of a flap extension on one side of an advancing box blank, including a head, an arcuate knife secured thereto and adjustable circumferentially thereof, a second knife extending axially of the head, a holder for said last mentioned knife and adjustable circumferentially of said head, a cam for adjusting said last mentioned knife in a radial plane, a clamp for holding the knife in adjusted position, and a member for locking both the blade and the cam in selected position in respect to the holder.

9. A device adapted to be mounted on a rotary slitter head, for making the end cuts of a flap extension on one side of an advancing box blank, including a head, a knife extending axially of the head, a holder for said knife and adjustable circumferentially of said head, a cam for adjusting said knife in a radial plane, a clamp for holding the knife in adjusted position, and a member for locking both the blade and the cam in selected position in respect to the holder.

10. A device for making transverse cuts in an advancing box blank, comprising a knife holder presenting a socket, and split along two planes substantially at right angles to each other to form two separable sections, a knife in one of the splits between said sections, a member in said socket for adjusting said knife outwardly from said holder, and means passing through said socket for holding said sections together against said knife.

11. A device for making transverse cuts in an advancing box blank, including a knife holder comprising two relatively movable sections, one of which has an inner curved surface bounding a socket, a knife between said sections, a rotatable member in said socket for adjusting said knife outwardly from said holder, and having a curved surface substantially conforming with and engaging said first mentioned surface, and means for clamping both said adjusting member and said knife between said sections.

12. A device for making transverse cuts in an advancing box blank, comprising a knife holder having a socket, a knife in said holder, a cam member rotatable in said socket for adjusting said knife outwardly from said holder, and means for clamping said knife in adjusted position.

ROBERT F. MORITZ.
